UNITED STATES PATENT OFFICE.

FRANK D'ONOFRIO, OF WILMINGTON, DELAWARE.

FIGURE TOY.

Application filed July 21, 1923. Serial No. 653,040.

To all whom it may concern:

Be it known that I, FRANK D'ONOFRIO, a citizen of United States of America, residing at Wilmington, in the county of New Castle and State of Delaware, have invented new and useful Improvements in Figure Toys, of which the following is a specification.

This invention relates to improvements in 10 toys and has for an object the provision of a toy which will simulate a man or other figure playing a hand organ or like musical instrument.

Another object of the invention is the provision of a toy which also includes a movable figure representing a monkey or other animal and actuated by the mechanism which actuates the musical instrument so as to add to the novelty and attractiveness 20 of the toy.

Another object of the invention is the provision of a toy of the above character which is simple in construction, reliable in operation and may be manufactured at a moderate 25 cost.

With the above and other objects in view, the invention further includes the following novel features and details of construction, to be hereinafter more fully described, illustrated in the accompanying drawings and pointed out in the appended claims.

In the drawings:

Figure 1 is a side elevation of a toy constructed in accordance with the invention.

Figure 2 is a front elevation thereof.

Figure 3 is a vertical sectional view.

Figure 4 is an enlarged vertical section taken substantially on the line 4—4 of Figure 1.

Figure 5 is a similar view on the line 5—5 of Figure 1.

Figure 6 is a side elevation of the casing or platform, the view looking at the opposite side of the casing from that shown in 45 Figure 1.

Referring to the drawings in detail wherein like characters of reference denote corresponding parts, the reference character 10 indicates a casing which constitutes a base 50 or platform having a figure indicated at 11. This figure represents a man carrying in one hand a cane or stick 12, the other arm being movable at the shoulder as indicated at 13 and at the elbow as indicated at 14.

55 This figure supports a box 15 and the latter has mounted therein a rotatable shaft

16. Extending radially from the shaft 16 and movable therewith is a plurality of thin spring fingers 17 which are adapted to engage projections 18 which extend inwardly 60 from a cylinder 19 located within the box, the said cylinder being stationary.

Mounted upon the shaft 16 is a grooved pulley 20 and extending around this pulley is a belt or cord 21. This belt or cord passes 65 around a grooved pulley or pulleys 22 mounted for rotation within the figure and the belt or cord passes downward through one leg of the figure into the casing or platform 10.

Mounted within the casing 10 is a shaft 23 which is provided with a grooved pulley 24 around which the belt or cord also passes, while secured to the shaft 23 is one end of a coiled spring 25, whose opposite end is secured to the casing as indicated at 26. This spring provides a motor which may be wound or tensioned to supply power through the belt or cord 21 for the rotation of the shaft 16 and the production of musical sounds through contact of the fingers 17 with the arms 18.

The shaft 23 extends through the casing and is provided with a crank handle 27, whereby the spring 25 may be tensioned, 85 while secured upon the shaft 23 is a ratchet wheel 28 which is engaged by a dog 29. This provides means for holding the shaft against rotation even though the spring is tensioned. The opposite end of the shaft 23 90 also extends through the casing 10 and is provided with a disk 29, while engaging this disk is a spring tensioned rod 30 which provides sufficient friction to retard unwinding movement of the spring 25 and permit 95 the shaft 23 to slowly operate. This friction may be relieved by engaging the upper end 31 of the arm over the top edge of the casing 10.

Mounted upon the box 15 is a figure 32 100 representing a monkey, the legs of which are jointed as at 33, while the feet are pivotally secured to the top of the box as shown at 34. Secured to the body of the figure 32 and extending downwardly through the top 105 of the box is a rod 35, whose inner end is enlarged as at 36 to engage the surface of a cam 37. This cam is mounted upon the shaft 16 so that when the said shaft is rotated the rod 35 will be reciprocated to move 110 the figure 32 vertically so as to simulate dancing. The monkey or figure 32 carries a

tray 38 which may be provided with bells or other sound producing devices, so that as the figure dances these bells or devices will produce sounds.

5 The shaft 16 extends through the box 15 and is provided with a crank 39 attached to the end of the jointed arm of the figure, so that as the toy is operated the effect of a man grinding a hand organ will be produced, while the figure 32 will simulate a dancing monkey.

10 The invention is susceptible of various changes in its form, proportions and minor details of construction and the right is here-
15 in reserved to make such changes as properly fall within the scope of the appended claims.

Having described the invention what is claimed is:-

20 1. A musical toy comprising a base, a figure mounted thereon and shaped to represent a human figure, a box supported thereby, sound producing mechanism within the box, a spring motor within the base, a motor shaft operatively connected to the sound
25 producing mechanism, whereby the latter may be actuated, a movable arm for the figure, means connecting the sound producing mechanism with the arm of the figure for moving said arm, a movable figure
30 mounted upon the box, means operatively connecting the sound producing mechanism

and the movable figure, whereby the latter may be actuated, a wheel mounted upon the motor shaft at one side of the base, a rod slidingly mounted upon the base for engaging the wheel to regulate rotation of the motor shaft, a spring for forcing the rod into such engagement and a lateral extension at one end of the rod to engage the base and prevent engagement of the rod and wheel.

2. A musical toy comprising a base, a hollow figure mounted upon the base, a box-like casing extending from the front of said figure and communicating with the interior of the latter, a figure supported by and movable upon the box, sound producing mechanism within the box, actuating mechanism also located within the box and operatively connected to the movable figure and to the sound producing mechanism, means connecting one arm of the first mentioned figure to said actuating mechanism, a motor within the base and means extending through the first mentioned figure and connecting the motor and actuating mechanism, whereby operation of the motor will move the arm of the first mentioned figure, operate the sound producing mechanism and move the movable figure, all in simulation of an organ grinder and a dancing figure.

In testimony whereof I affix my signature,
FRANK D'ONOFRIO.
